UNITED STATES PATENT OFFICE

JOSEPH DISTER, OF HAMILTON, OHIO, ASSIGNOR TO AMERICAN CAN COMPANY, OF NEW YORK, N. Y., A CORPORATION OF NEW JERSEY

CAN

Application filed January 10, 1925. Serial No. 1,534.

My present invention relates to containers particularly adapted for packaging food products, such as coffee, which must be hermetically sealed for preservation in storage and shipment and which are removed from the container as required for use, so that both an hermetic closure and a temporary reclosure are desirable.

A highly important feature of the invention is the provision of a can of this character which is, so far as possible, of the standard construction of the so-called "sanitary" or "packers" can and which, therefore, are adapted to be formed and handled by standard processes and machinery, both in the factory and the packing plant.

The invention contemplates, in this connection, the use of a standard body and bottom end, as well as a top end which may be seamed to the body in the usual manner and is provided with a scored boss adapted to have an opening formed therein by breaking away the metal along the lines of scoring, the friction reclosure being provided to fit upon said boss to close said opening and protect the contents from dust and foreign particles after the can has been originally opened.

An important advantage of the can provided by my invention is that the boss referred to above and the friction reclosure are disposed within the overall height of the can, i. e., beneath the top of the seamed edge of the hermetic cover and the cans may, therefore, be packed in the usual packing cases and stacked end upon end, in firmly supported relationship and without increasing the space required.

A further object of the invention is the provision of a can provided with weakening score lines adapted to be broken without the use of a key and providing an eccentric opening which may be used as a pouring spout, or to permit insertion of a spoon for removal of the product in measured quantity, as desired.

The can of my invention is also adapted for paint and other liquid contents and in this connection it is to be noted, as a special advantage, that the dispensing portion is projected outwardly from the top of the can, thus avoiding any pockets or obstructing portions

on the interior which would interfere with the pouring of the contents.

Numerous other objects and advantages of the invention will be apparent as it is better understood from the following description, which, taken in connection with the accompanying drawings, discloses a preferred embodiment thereof.

Referring to the drawings,

Figure 1 is a top plan view of the container constructed in accordance with my invention;

Fig. 2 is a cross section of the upper part of the container, showing the temporary closure in spaced relationship, the same being also illustrated in dotted lines in its position upon the can;

Fig. 3 is a similar view after the scored section has been broken away and the metal bent inwardly to permit removal of the contents;

Fig. 4 is a partial plan view of the can after it has been opened, as shown in Fig. 3; and

Fig. 5 is a perspective view of the can in pouring position.

In said drawings, I have shown, for illustrative purposes only, a preferred form of my invention, in which the reference character 11 indicates the body of the can, which may be of the usual cylindrical form and is provided at the top with an hermetic closure 12, which is secured to the upper edge of the body in a double seam 13, the bottom end of the can being closed in the ordinary way by an end member 14. It will be observed that the ends 12 and 14 may be applied by the high speed machinery now in use, in exactly the same way as the ends of standard cans of the "sanitary" or "packers" type are applied. The upper end 12, however, is drawn to provide an integral boss 15, surrounded by a channel 16 and having score lines 18 and 19 on the top thereof adapted to be broken away by any suitable instrument, the line 18, in the present instance, extending circumferentially around a portion of the top of the boss and the line 19 extending radially from the center into said circumferential line, so that when said lines are broken, the metal will extend into the can in the form of lips 21, which may be bent inwardly to any de-

sired extent, according to the manner of removal contemplated. If it be desired to remove the contents with a spoon, obviously said lips may be bent in far enough to provide a relatively large opening and it will be understood that, from certain aspects of the invention, the particular form of the score lines or type of opening provided is not material.

10 A reclosure 22 is provided and adapted to fit upon the boss 15, said reclosure having an outwardly extending shoulder 23 and a depending wall 24, which latter is adapted to frictionally engage the vertical wall 17 of the boss and to extend into the channel 16. When so positioned, the top of the reclosure is below the top of the seam 13, as shown in Fig. 2, so that it will not, in any way, interfere with the stacking or handling of the cans. The shoulder 23 provides a convenient means of removal of the member 22, which may be pried off by inserting a suitable instrument beneath said shoulder.

15 The frictional fit between the flange 24 of the reclosure and the wall 17 of the boss is sufficiently tight to hold the aromatic flavors of coffee, or like goods, even after the seal is broken, and yet the reclosure may be readily removed by reason of the provision of the shoulder 23.

20 An important practical advantage resides in the fact that the boss 15 is formed integrally with the cover 12 and need not be soldered or otherwise sealed in place, as has been necessary in certain constructions in the past.

25 When opened along the score lines 18 and 19 arranged as indicated in the drawings, a restricted, eccentrically disposed pouring opening is provided through which the material may be poured in a stream, as indicated at 25, the stream being small enough so that the pouring may be accurately controlled in measuring out a desired quantity for use, and it will be observed that this opening has a pouring lip located beyond and above the depressed central portion of the top of the can so that the stream of material being poured need not spill on the can top.

30 It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

35 A can comprising a body, top and bottom end members hermetically seamed to said body, the top member being formed with an integrally raised boss arranged near one side of the can to provide a pouring nozzle, and a friction reclosure adapted to tightly engage

outside of said boss, said boss having a scored line around a portion of its circumference near the neighboring edge of the can body, and with a radial scored line extending from said circumferential line inward toward the middle of said boss, whereby a portion of the boss may be depressed and separated into two triangular portions, to provide a pouring opening.

JOSEPH DISTER.
